UNITED STATES PATENT OFFICE

CHARLES E. UNDERWOOD AND JAMES A. BEATTY, OF BETHLEHEM, PENNSYLVANIA,
ASSIGNORS TO BETHLEHEM STEEL COMPANY

FUEL-DISTRIBUTUTING APPARATUS

Application filed October 10, 1925. Serial No. 61,819.

This invention relates to a new and useful improvement in self-adjustable means for conducting fuel to heating furnaces. It relates more particularly to coke ovens of that general type, wherein the oven consists of a battery of rectangular coking chambers, the vertical walls of which are heated by vertical flues disposed transversely of the longitudinal axis of the oven battery. The heating gas, which may be the permanent gas from the coking operation itself, or it may be a gas of low calorific value from other sources, is admitted to the vertical flues, together with the requisite amount of air, preheated by its passage through the hot checker-work of the regenerating chambers disposed in the foundations of the oven battery.

According to the particular design of the oven used, these vertical flues may be grouped in sets of half their number, wherein one-half of a row of flues is under combustion, whereas the other half is conveying the products of combustion to the exhaust flues leading to the regenerators, the respective functions of the two groups being reversed at predetermined intervals of time. Or, again, the groups may consist of two or more flues, a group for combustion alternating with a group for exhaust, said groups being likewise reversible.

In all these cases, the gas is conveyed to the flues by two gas mains, one on the charging side and one on the discharging side of the oven, said mains being placed parallel to the longitudinal axis of the oven, and having suitable branches to communicate gas from each main to the transverse sole flues, which feed the vertical heating flues of each chamber. At the entry of each sole flue, a nozzle is normally interposed, generally known in the art as a gas gun, to which the aforesaid branches are connected. The nozzle end of the gas gun fits loosely in the brick construction of the sole flue, being suitably luted with cement or plaster. Owing to the expansion of the gas main and consequent displacement of the gas gun, considerable difficulty is encountered in preserving gas tight joints at the entry of the gas gun nozzle into the sole flue.

The invention therefore has for an object, an improvement in the construction of gas injecting conduits, whereby permanent connection to the sole flues is obtained irrespective of the expansion and contraction of the gas mains.

Apparatus made in accordance with our invention is illustrated in the accompanying drawings, forming a part of this specification, in which:

Fig. 1 is a transverse section through a portion of the coke oven battery showing our improvement applied thereto;

Fig. 2 is a longitudinal sectional view of the gas gun and the metallic conduit forming the terminal section of the sole flue;

Fig. 3 is a sectional view taken along the line III—III of Fig. 2; and,

Fig. 4 is an end elevation of the gas gun.

In Fig. 1, we show a gas main 11, a swivelling connection 12, a gas gun 13, a metallic conduit 14, a sole flue 15, vertical heating flues 16, gas burners 17, and air ports 18.

In Figs. 2, 3 and 4, we show the construction of the gas gun 13 and the metallic conduit 14 in greater detail. The gas gun 13 has an inspection plate 21 secured to the body of the gun by studs 22 held in suitable lugs projecting from the gun body, a gas inlet connection 23 and a depending bracket 24 suitably slotted for bolts, whereby the gun may be attached to a buckstay 19 (as in Fig. 1) or to any convenient portion of the oven structure.

The delivery end 25 of the gas gun is of spherical shape externally so as to conform with a spherical seat 26 in the conduit 14. A split gland or neck ring 27 enters a stuffing box 28, and is secured to the conduit 14 by the stud bolts 29.

The conduit is provided with a gas outlet 31 to communicate with the burner of the first vertical flue, and is faced and grooved at 32 to conform with the end brick section of the sole flue 15. The inlet end 33 of the conduit 14 is furthermore flared out, so as to permit of the unimpeded flow of gas when the gas gun occupies a position of extreme angular displacement from normal. As shown in the drawing, the flared out portion

33 is of ogival profile, said ogive commencing at the spherical seat 26 and terminating at the bore 34 of the conduit, the diameter of which conforms to the bore of the brick sections forming the sole flue.

5 Owing to the ball and socket joint between the parts 13 and 14 and to the stuffing box 28, a tight joint is always maintained between the gas gun 13 and the metallic conduit 14 10 even though the former be displaced from its position of axial alignment with the latter due to expansion and contraction of the gas main 11. In addition, the metallic conduit section 14 takes the place of the terminal brick 15 section of the sole flue hitherto used, whereby the usual attrition and breaking away of the brick wall is entirely overcome.

10 In cases where the coke oven is of the type having continuous heating flues disposed 20 horizontally on either side of the coking chamber, gas and air being admitted at different points in the heating flues, the entry of gas may be effected by the means above described, except that the gas outlet 31 communicating with the first flue in the vertical flue type of oven may be eliminated, all the 25 gas passing through the bore 34 of the conduit 14.

15 It will likewise be obvious to those skilled in the art that the features embodied in our invention, viz, a ball and socket joint between a fuel gun and a metallic conduit communicating with a brick flue, said conduit having its bore flared out so as not to impede the flow 30 of fuel at extreme angular displacements of the gun, may be similarly utilized in furnaces of types other than those we have described, wherein adjustability of the fuel gun position is particularly desired.

20 While we have shown our invention in but one form, it will be obvious to those skilled in the art that it is not so limited, but is susceptible of various other changes and modifications without departing from the spirit 25 thereof, and we desire, therefore, that only such limitations shall be placed thereupon as are imposed by the prior art or as are specifically set forth in the appended claims.

25 Having thus described the invention what 30 we claim as new and desire to secure by Letters Patent is:

1. The combination with a furnace having a gas combustion chamber, of a gas conduit mounted within the furnace structure 35 communicating with the gas combustion chamber, said conduit having a metallic section terminating adjacent the external surface of the masonry structure, gas conducting means between the gas main and the gas 40 conduit including a metallic conducting element pivotally connected to the metallic end section of said gas conduit.

2. The combination with a furnace having a gas combustion chamber, of a gas conduit 45 extending from the exterior of the furnace

into the masonry structure thereof and communicating with the gas combustion chamber, said conduit having a metallic section terminating adjacent the external surface of the masonry structure, a gas main, gas conducting means between the gas main and the gas conduit comprising a metallic element communicating with the metallic section of the conduit and swivelly connected thereto.

3. The combination with a furnace having a gas combustion chamber, of a gas conduit extending from the exterior of the furnace into the masonry structure thereof and communicating with the gas combustion chamber, said conduit having a metallic section terminating adjacent the external surface of the masonry structure, a gas main, gas conducting means between the gas main and the gas conduit comprising a metallic conducting element united to the metal section of the gas conduit by a ball and socket joint.

In testimony whereof I hereunto affix my signature this 30th day of September, 1925.

C. E. UNDERWOOD.

In testimony whereof I hereunto affix my signature this 30th day of September, 1925.

JAMES A. BEATTY.
